ENGINE STARTER GEARING

Arthur R. Tobias, Elmira, N. Y., assignor to Bendix Aviation Corporation, Elmira Heights, N. Y., a corporation of Delaware

Application June 9, 1950, Serial No. 167,103

1 Claim. (Cl. 74—7)

1. A drive assembly comprising

The present invention relates to engine starter gearing, and more particularly to that type of drive in which the engagement of a drive pinion with an engine gear is secured by threaded traversing means.

In drives of this type where the pinion is traversed longitudinally into mesh with the engine gear by acceleration of a screw shaft, it is customary to provide some means for relieving abutting or jamming conditions which sometimes occur when the teeth of the pinion collide with the teeth of the engine gear. Such means is usually in the form of a longitudinally yielding connection between the starting motor and pinion which permits the pinion to pause in its traversal and provide time for the torque from the screw shaft to build up and index the pinion into proper registry with the tooth spaces of the engine gear. In the patent to McGrath, 1,822,163, the same problem is solved by providing means extraneous to the threaded connection for indexing the pinion when its longitudinal movement is interrupted by tooth abutment with the engine gear.

It is an object of the present invention to provide a starter drive having novel means for indexing the pinion in case its meshing movement is arrested.

It is another object to provide such a device in which the indexing means is positive in its action and permits no free lost motion of the pinion.

It is another object to provide such a device in which the indexing means is incorporated in the body of the drive without requiring any added or extraneous elements.

Further objects and advantages will be apparent from the following description taken in connection with the accompanying drawing in which:

Fig. 1 is a side elevation partly broken away and in section of a preferred embodiment of the invention showing the parts in idle position.

Fig. 2 is a similar view showing the parts in cranking position.

Fig. 3 is a similar view showing the parts in the positions assumed in case of tooth abutment between the drive pinion and engine gear; and

Fig. 4 is a side elevation of the drive rotated by 90° from the position illustrated in Fig. 3.

In Fig. 1 of the drawing there is illustrated a power shaft 1 on which a driving clutch member 2 is fixedly mounted as by means of a cross pin 3 retained in position by a ring 4. Clutch member 2 has overrunning clutch teeth 5 adapted to engage corresponding teeth 6 on a screw

shaft 7 which is slidably journaled on the power shaft.

A pinion 8 is journaled on the power shaft 1 for longitudinal movement into and out of mesh with an engine gear 9. A cup 11 is rigidly mounted at one end on the pinion as indicated at 12, and at its other end is provided with a radial flange 13 which is anchored as indicated at 14 in the open end of a barrel member 15 enclosing the drive. The barrel 15 is provided with a pair of inclined or spirally arranged slots 16 (Fig. 4), and a control nut 17 is threaded on the screw shaft 7 and provided with a radial flange 18 having diametrically arranged lugs 19 extending into and having a loose sliding fit in the spiral slots 16. Means for normally maintaining the control nut with its lugs 19 at the left hand ends of the slots 16 and for yieldably resisting longitudinal movement of the control nut to the right in the barrel 15 is provided in the form of a cylinder 21 of elastically deformable material such as rubber, seated at one end on the control nut against the flange 18 and at its other end bearing against the radial flange 22 of a ferrule 23 which is clamped against the flange 13 of sleeve 11 by crimping over the end of the barrel 15 as shown at 14.

The barrel 15 is provided with a reduced extension 24 terminating in an inwardly directed flange 25. An anti-drift spring 26 bears at one end against the flange 25 of the barrel, and at its other end against a flange 27 of ring 4 on which it is seated.

In operation, starting with the parts in the positions illustrated in Fig. 1, rotation of the power shaft 1 in the direction of the arrow (a) causes the screw shaft 7 to be rotated by reason of its clutch connection 5, 6 with the drive clutch member 2. Control nut 17 is thereby traversed to the right, moving the barrel 15, cup 11 and pinion 8 through the rubber cylinder 21 until the pinion is meshed with the engine gear 9 whereupon the flange 25 of the barrel engages the driving clutch member 2 as shown in Fig. 2. Further longitudinal movement of the control nut causes compression of the rubber cylinder, whereby the control nut 17 is yieldably constrained to rotate with the screw shaft 7, which rotation is transmitted by lugs 19 to the barrel 15 and pinion 8.

If, during the meshing movement, a tooth of the pinion abuts against a tooth of the engine gear, the movement of the pinion is arrested while the control nut 17 continues to move forward compressing elastic member 21 as shown in Fig. 3. Inasmuch as the slots 16 in the barrel

are inclined or skewed as shown in Fig. 4, the consequent longitudinal movement of the lugs 19 of the control nut in the slots 16 causes the barrel, and consequently the pinion 8, to be indexed by the camming action of the lugs in the slots 5 so as to bring the teeth of the pinion into proper registry with the tooth spaces of the engine gear. As soon as this happens, the expansion of the elastic member 21 snaps the pinion into initial mesh, and meshing and cranking proceed as 10 usual.

When the engine starts, the acceleration of the pinion, barrel, and control nut with respect to the screw shaft causes the members to return to idle position with the assistance of the anti-drift spring 26; the overrunning clutch 5, 6 permitting the parts to overrun in idle position until their 15 rotary inertia is dissipated.

Although but one form of the invention has been shown and described in detail, it will be 20 understood that changes may be made in the design and arrangement of the parts without departing from the spirit of the invention.

I claim:

In an engine starter drive a power shaft, a 25 screw shaft mounted thereon, means for connecting the screw shaft to rotate with the power

shaft, a pinion slidably journaled on the power shaft for movement into and out of mesh with an engine gear, a barrel member surrounding the screw shaft, fixed at one end to the pinion and slidably journaled at its other end on the power shaft, a control nut on the screw shaft having an inclined driving connection to the barrel, and yielding means in the barrel opposing longitudinal movement of the nut on the barrel; in which the barrel is provided with diametrically arranged spiral slots, and the control nut is formed with radially extending lugs loosely fitting in the spiral slots, and the yielding means is arranged between the control nut and pinion so as to oppose longitudinal movement of the control nut in the barrel toward the pinion.

ARTHUR R. TOBIAS.
